UNITED STATES PATENT OFFICE

2,429,553

LAMP

Anthony F. Jasinski, Chicago, Ill., assignor of one-third to Sam A. Edelman and one-third to Samuel Stern, both of Chicago, Ill.

Application August 6, 1945, Serial No. 609,077

1 Claim. (Cl. 240—81)

1
The invention relates to light fixtures and particularly to lamps having a base, a post and a head carried on the post.

Lamps and particularly floor lamps present a shipping problem by reason of the fact that even in large cartons only a few lamps can be packed because of the size of the base and the narrow diameter of the post.

The present invention, therefore, aims at providing a floor lamp where the base may be readily removed without disturbing the electric wiring passing from the head through the post and emerging from the base without the use of washers or lock nuts.

A further object constitutes the provision of a floor lamp wherein the base is constructed to permit removal thereof without necessitating the removal of the electric plug and leaving the wiring intact.

With these and other objects in view which will become apparent from a perusal of the invention, the latter comprises the means described in the following specification particularly pointed out in the claims forming a part thereof, and illustrated in the accompanying drawing, in which

Fig. 1 is an elevational view of a floor lamp in which the invention is incorporated.

Fig. 2 is an enlarged section on the line 2—2 of Fig. 1.

Fig. 3 is a section on the line 3—3 of Fig. 2.

Fig. 4 is a view similar to Fig. 3 with the parts in disassembled relation, and

Fig. 5 is a top plan view of a base.

Referring to the views of the drawing, the lamp comprises a base 10 to which is secured a post generally designated by 11 carrying at the upper bend a lamp head not shown surrounded by a shade 12.

The post 11 comprises a tube 13 surrounding an inner pipe 14 which is provided with threads 15 at the lower end. The pipe 14 is threadedly engaged in a threaded aperture 16 in the base formed at the top with three openings 18 of standard construction whereby a plurality of spokes 19 are formed.

The base is surmounted by an insert or cover 20 and an ornamental break 21 is interposed between the tube 13 and the insert. These elements are further secured by a lock nut 22 against accidental turning.

The wiring 23 leads from the terminals of the sockets through the pipe 14 and base and is provided with a plug 24 for insertion in a wall socket of a home to supply current to the lamps of the head.

2

The parts thus far described are standard construction of floor lamps and per se do not form a part of the invention.

The shipping of lamps of this type is quite expensive as only a few lamps can be packed in large containers since the head and post are considerably smaller in diameter than the comparative large and heavy base.

It is for this reason that it is very desirable to enable speedy and convenient removal of the base, so that a larger number of lamps may be assembled in the shipping container and the bases may be packed and shipped separately.

To remove the bases it is important that the wiring and the attached plug shall remain undisturbed so that no expert help is necessary in the removal or assembly of the base.

To this end the aperture 16 is provided with a slot 25 which places in communication one of the openings 18 in the base with the aperture 16. Thus when the base is to be removed the base is screwed off from the pipe 14, and wire 23 is shifted laterally through the slot 25 into the large opening 18 which is large enough to clear the plug 24, obviating thereby any necessity for removing the plug 24 in order to permit disassembly of the base.

In Fig. 5 a slight modification is shown where the base 30 is solid.

30 Here the central aperture 31 is connected by a slot 32 with an opening 33 which is large enough to clear the plug upon removal of the base.

Attention is called to the fact that the post and head may be assembled and wired as an entity which may be carried out on tables, whereas the assembly of the lamp together with the base requires considerable floor space which is thus eliminated by the invention.

The embodiments of the invention shown in the drawing are merely illustrative of the manner of permitting convenient removal of the base.

Various changes and alterations may be made without departing from the spirit of the invention.

45 I, therefore, include all variations, modifications and revisions constituting departures within the scope of the invention as defined in the appended claim.

50 I claim:

In a lamp having a post surrounding a metal pipe threaded at the lower end to be directly and threadedly secured in the central aperture of a metal base, and wiring leading through said pipe to a plug, an opening in said base spaced from

the central aperture and of a diameter sufficient to clear the plug, a slot affording communication between said opening and aperture to permit the plug attached to the wiring to pass through the opening and to slide the wiring through said slot so as to enter the central aperture of the base and a cover member secured to said pipe and overlying the top of said base to conceal the opening and slot in said base.

ANTHONY F. JASINSKI.
